UNITED STATES PATENT OFFICE.

WILLIAM B. ALTIICK, OF LANCASTER, PENNSYLVANIA.

TELEPHONE-CABINET.

SPECIFICATION forming part of Letters Patent No. 756,091, dated March 29, 1904.

Application filed May 16, 1902. Serial No. 107,585. (No model.)

To all whom it may concern:

Be it known that I, WILLIAM B. ALTIICK, a citizen of the United States, residing at Lancaster, in the county of Lancaster and State of Pennsylvania, have invented certain new and useful Improvements in Telephone-Cabinets; and I do hereby declare the following to be a full, clear, and exact description of the invention, such as will enable others skilled in the art to which it appertains to make and use the same.

This invention relates to improvements in a telephone cabinet or closet of that class in which a suitable casing or frame is provided with a folding or extensible wall made in one section and adapted to close or open the forward portion of said casing or frame, with the top and one side thereof provided with transparent plates for the admission of light.

The object of the invention is to provide a compact folding or extensible cabinet for the purpose of insulating a telephone or cutting it off as much as possible from all outside sounds or noises while using said instrument, said noises and sounds being extremely annoying as well as detrimental to satisfactory communication; and the invention may be considered as an improvement on that embodied in the previous application for Letters Patent, filed October 8, 1901, Serial No. 77,963, greatly simplifying the construction.

The elements of the invention will severally and at large appear in the following description, and they will be separately or combinedly set forth or pointed out in the appended claims.

The purposes of the invention are attained by the mechanism, devices, and means illustrated in the accompanying drawings, with similar reference characters to designate like parts throughout the several views, in which—

Figure 1 is a perspective view of a telephone-cabinet embodying the elements of the invention with the central portion broken away, the upper portion thereof closed, and the lower portion opened; Fig. 2, a vertical central section practically on the line x x x x in Fig. 1; Fig. 3, a direct top view of Fig. 1 with the portion practically above the line

y y y removed, showing the wall partially extended, with the upper ends of its posts, wings, and lining appearing in full top view; Fig. 4, a direct top view of the lower portion of Fig. 1; Fig. 5, an inverted view of the top portion removed from Fig. 1; Fig. 6, a front and a side elevation, both enlarged, of the upper end of one of the wall-posts; Fig. 7, a front and a sectional elevation, also enlarged, of the lower end of the same post; and Fig. 8, a detached plan of the extensible wall with rollers and lining removed.

In the drawings, A designates the casing or the affixed portion of the cabinet referred to in the opening paragraph hereto, which cabinet, like that in said former application, has the required dimensions to house a telephone as well as to completely inclose the person of the individual using said instrument, the cabinet being adapted to be placed in upright position and rigidly affixed against a side wall of a hall, room, or office containing said telephone without encumbering said hall, room, or office, occupying a minimum of space therein, and when not in use being practically out of the way; but the wall is not shown.

In the construction of the casing or frame A is shown a back board or wall-plate a of a size equal to the height and width of the cabinet and having at its upper end a forwardly-extending top plate a' , making a right angle therewith, with its rearward end edge rigidly secured thereto, as by nails or screws, said top plate having parallel straight side edges extending forward a prescribed distance from its rearward end, with its forward portion preferably circularly rounded, as shown, and having on its under surface, a short distance from the edge thereof, a depending wall or rib a'' , forming an inverted-L-shaped recess a'' the whole way around said edge, while against the outer face thereof is secured in any approved manner a strip a''' , forming with said recess a'' a channel a'''' , constituting a passage-way in which move vertically-disposed rollers guiding the upper end of the extensible wall, yet to be described, and in the body of the top plate is formed an aperture a''''' , which is closed by a transparent plate A' for the admission of light;

but two plates may be arranged in parallel planes with a space between them to close this aperture without changing the character of the invention. With its rear edge rigidly secured 5 to the lower end of said wall or back plate and arranged in a plane parallel to said top plate is a bottom plate a^s , being similar in horizontal size and contour to the top plate a' , said bottom plate having in its upper surface at 10 the required distance from the surrounding edge thereof a groove a^s , in which move swiveled rollers b^s , guiding the lower end of said extensible wall, while against the parallel straight edges of the top and bottom plates 15 $a' a^s$, as well as against the forward surface of the wall-plate a , are rigidly secured the upper and lower ends and the rearward edges of side boards a^s , and through an opening in one of said side boards is seated and secured a sash- 20 frame A^s , provided with a transparent plate A^s or a pair of such plates for the admission of light, thus completing the casing.

Inclosing or opening the forward portion of the casing or the open space between the top 25 and bottom plates thereof is an extensible and contractible wall B , comprising a rear end post b , a front end post b' , and the required number of intermediate posts $b^s b^s b^s b^s$, all of approved width and depth and having a length 30 practically equal to the distance between the top and bottom plates of the casing, between which plates they are mounted and intended to move to and fro, with their width and depth serving to accommodate the hinged wings, yet 35 to be described. The posts throughout the series have their adjacent side edges sidewise and inwardly rabbeted out, so as to form L-shaped recesses b^s in said side edges, into each of which recesses is placed one side edge of a 40 wall-wing b^s and hinged to the inner or rearward side of its post by two or more strap-hinges b^s , said wings in pairs having their other side edges meeting and hinged together by similar strap-hinges b^s , secured to the adjacent surfaces of the wings. These posts have 45 secured to the outer surfaces of their lower ends plates with swiveled arms or rods carrying on their lower ends directly under the posts pivoted rollers b^s , engaging in the groove 50 a^s of the bottom plate, supporting and guiding said posts in place, and the posts have secured to the outer surfaces of their upper ends plates with pairs of upwardly-projecting spindles, carrying thereon vertically-journalized 55 rollers b^s , engaging in the surrounding channel a^s of the top plate, each pair of rollers preventing its post from turning. These posts and wings thus hinged together and supported are provided with a lining B' , of any approved 60 material, entirely covering their inner surfaces from the forward side edge of the forward end post b' to the rearward side edge of the rearward end post b , along which edges said lining is rigidly affixed, as by rows of 65 headed tacks or nails b^s , driven into said posts,

and the lining extending from said rearward end post b up to and against the inner surface of the back or wall plate a , where its end edge is rigidly secured to the inner surface of the adjacent side board a^s ; also, by a row of headed tacks or nails driven into said side board, which tacks or nails are likewise designated by b^s , and said lining extension, with its rear end edge thus secured, constitutes a stop preventing the further forward progress of said rear end post when the wall is extended or the cabinet closed and yet by doubling or folding up allowing said post to move back against the back board a when the wall is contracted or folded or the cabinet opened, while hooks 70 b^{10} , driven into the inner surfaces of the intermediate posts b^s near their upper ends and engaging through the body of the lining adjacent to the upper edge thereof, serve to support said lining between said rear and forward end posts $b b'$. At the desired point the forward end post b' is provided with a knob or pin B^s , constituting a hand-grip, whereby the wall is extended in one direction and contracted or folded in another, as when closing 75 the cabinet. Against the forward edges of the side boards a^s are rigidly secured elastic or pliable strips B^s to engage against or to contact with the rear and front end posts when the cabinet is closed, closing 80 possible vents which may appear. When the cabinet is placed in position, a lining B^s , of any approved material, entirely covering the entire back board a , is placed between said board and the wall against which said cabinet 85 is to be erected, and a lining B' , of the same material, is placed between the bottom plate a^s and the floor upon which it is to stand, both for the purpose of insulating the cabinet and cushioning it from any vibration from the 90 building.

It will here be remarked that the cabinet hereinbefore described differs from that described in said former application, in this, that the side boards a^s are provided in addition to the back board supporting the top and bottom plates to constitute the casing A ; that one of the side boards a^s is provided with a transparent plate or two such plates in parallel planes for the admission of light in 105 addition to the plate or plates placed in the top plate a' ; that in the adjacent surfaces of the top and bottom plates the guide-recesses with the central grooves are omitted, the former plate having instead the vertical roller-guide channel a^s and the latter plate having instead the roller-guide groove a^s ; that the inclosing wall is composed of one section with all the wing-supporting posts movable instead of two sections with their rear end posts in 110 affixed positions; that said wall is adapted to close or open the space from and between the forward edges of the side boards a^s ; that said wall is adapted to be folded within the 115 space behind one of said side boards a^s when 120 125 130

the cabinet is open; that the portion of the wall-lining extension beyond the rear wall-post b in being secured to the post and to the adjacent side board a constitutes a stop preventing the movement of said post beyond the forward edge of said side board, and that the elastic strips B by their contact with the rear and front end posts of the wall when said wall is extended will close all vents or openings 10 that may be therebetween.

The invention having been thus ascertained and described and the manner in which it is performed fully shown and set forth, what is considered new, and desired to be secured by 15 Letters Patent, is—

1. In a cabinet, a casing comprising a back wall-plate, a top plate and a bottom plate, side boards secured to the back plate and extending from the top to the bottom plate, packing-strips along the front edges of the side boards, an extensible wall comprising movable posts and foldable wings adapted to close the forward portion of the casing between the top and bottom plates, and means on said casing 25 for admitting light thereto, substantially as described.

2. In a cabinet, a casing comprising a wall-plate with top and bottom plates projecting in parallel planes from the upper and lower 30 ends thereof but perpendicular therewith, and side boards secured to said top and bottom plates and to said wall-plate, said side boards closing the rearward portions of the sides of said casing, with transparent plates in said top plate and one of said side boards, and an extensible wall made in one section but composed of movable posts and foldable wings adapted to close or open the forward portion of said casing between said top and bottom 35 plates, substantially as described and for the purpose hereinbefore set forth.

3. In a cabinet, a casing comprising a back wall-plate, a top plate and a bottom plate projecting from the said wall-plate, side boards 45 secured to the wall-plate and extending from the top to the bottom plate, said top plate and side boards having openings, transparent plates seated in the openings, and an extensible wall having one end secured to one of the 50 side boards and comprising movable posts and hinged wings adapted to close the forward portion of the casing, substantially as described.

4. In a cabinet, a casing, an extensible wall comprising movable posts and hinged wings 55 adapted to close the casing, and a lining cov-

ering the interior of said wall, substantially as described.

5. In a cabinet, a casing comprising a back plate, a top plate, a bottom plate and an extensible wall composed of movable posts and 60 hinged wings, a cushioning-packing covering the back of the said back plate, and a cushioning-packing covering the bottom of the said bottom plate, substantially as described.

6. In a cabinet, a casing comprising a back 65 wall-plate, a top plate and a bottom plate projecting from said wall-plate, said plates having semicircular forward ends and provided with a groove and a guideway, side boards secured to the wall-plate and extending from 70 the top to the bottom plate, an extensible wall composed of movable posts and hinged wings adapted to close and open the forward portion of the casing, and vertical rollers engaging in said groove and way for supporting and guiding 75 said wall, substantially as described.

7. In a cabinet, a casing, a closure for said casing comprising movable posts and hinged wings, swiveled rollers for supporting the closure, and rollers for guiding the closure, 80 substantially as described.

8. In a cabinet, a casing having a back plate provided with parallel top and bottom plates, said plates having rearward straight sides and semicircular forward ends, side-closing boards 85 secured to the said straight sides, said top plate provided with a horizontally-disposed roller-way and said bottom plate having a corresponding roller-groove, an extensible wall composed of movable posts each having a pair 90 of vertically-journaled rollers at its upper end engaging in said way and a swiveled roller on its lower end engaging in the groove, pairs of wings hinged together and having their inner edges hinged to the posts, a lining covering 95 said posts and wings rigidly secured to the forward end post and to the rear end post, said lining extending back of said rear post and secured to the back plate, transparent plates secured in the top plate and one of the side 100 boards, and means for moving the extensible wall to open and close the forward portion of the casing, substantially as described.

In testimony whereof I affix my signature in presence of two witnesses.

WILLIAM B. ALTICK.
